UNITED STATES PATENT OFFICE.

HERBERT P. WHITCOMB, OF LANCASTER, NEW HAMPSHIRE.

TRAIN-CHECK HOLDER.

1,201,407.

Specification of Letters Patent. Patented Oct. 17, 1916.

Application filed November 23, 1914. Serial No. 873,639.

To all whom it may concern:

Be it known that I, HERBERT P. WHITCOMB, a citizen of the United States, residing at Lancaster, in the county of Coos, State 5 of New Hampshire, have invented certain new and useful Improvements in Train-Check Holders; and I do hereby declare the following to be a full, clear, and exact description of the invention, such as will enable others skilled in the art to which it 10 appertains to make and use the same.

This invention relates to train check holders.

The object of the invention resides in the 15 provision of a device of the character named which may be readily attached to the seat of a car and which is adapted to hold a train check for each passenger in the seat in such manner that the conductor will 20 easily see the punch marks therein.

With the above and other objects in view the invention consists in the details of construction and in the arrangement and combination of parts to be hereinafter more 25 fully described and particularly pointed out in the appended claim.

In describing the invention in detail reference will be had to the accompanying drawings wherein like characters of reference 30 denote corresponding parts in the several views, and in which—

Figure 1 is a perspective view of a fragment of a car seat showing the improved check holder applied; Fig. 2, is an enlarged 35 plan view of the holder; Fig. 3, a vertical longitudinal section of same; Fig. 4, a transverse section of the holder; Fig. 5, a perspective view, of the central section of the holder; Fig. 6, a perspective view of the 40 inner section of the holder, and Fig. 7 is a fragmentary view of the upper portion of the outer member of the device.

Referring to the drawings the train check holder is shown as comprising an outer 45 member A, a central member B, and an inner member C. The outer member A is U-shaped in cross section and includes arms 10 and 11, and an arm connecting portion 12. The free ends of the arms 10 and 11 are re- 50 ceased to form shoulders 13. These arms 10 and 11 at the upper end of the member A are provided respectively with extensions 14, while the lower end of the arm connecting portion 12 is provided with an extension

15 having a screw passage 16 therethrough. 55 Likewise the extensions 14 are provided with screw passages 17 which are interrupted by the recesses forming the shoulders 13. The central member B is also U-shaped in cross section and includes arms 18 and 19, 60 and an arm connecting portion 20. The free ends of the arms 18 and 19 are provided respectively with laterally extending wings 21 which bear against respective shoulders 13, the major portion of the member B being 65 projected into the member A as will be obvious. The wings 21 are provided respectively with recesses 22 which mate with the interrupted portions of respective passages 17. Integral with the arm connecting portion 20 is a leaf spring 22' which bears 70 against the inner side of the arm connecting portion 12 of the member A.

The inner member C comprises a plate 23 which bears against the wings 21 and is provided in its side edges with recesses 24 which mate with respective interrupted portions of the passages 17. The lower end of the plate 23 is provided with an extension 25 which projects between the arms 18 80 and 19. A leaf spring 26 is integral with one side of the plate 23 and bears against the inner side of the arm connecting portion 20 of the member B. Suitable screws 27 are passed through the passages 17 and recesses 85 22 and 24 and then into the car seat frame and in this way the various members of the holder are held to the car seat in assembled relation and in such manner as to form two compartments in each of which may be inserted a train check. These checks are of course held between the spring 22 and arm connecting portion 12, and between the spring 26 and arm connecting portion 20. The checks may be adjusted readily to different heights so that the punch marks on 90 each check may be readily observed by the conductor as he passes through the aisle. 95

What is claimed is:—

A train check holder comprising an outer 100 member having a U-shaped cross section, a central member having a U-shaped cross section disposed in the first member with its arm connecting portion spaced from the arm connecting portion of the outer member, an 105 inner member spanning the arms of the central member, a common means for securing said members in assembled relation and to a

support, a spring carried by the arm connecting portion of the central member and bearing against the arm connecting portion of the outer member, and a spring carried by the inner member and bearing against the arm connecting portion of the central member.

In testimony whereof, I affix my signature, in the presence of two witnesses.

HERBERT P. WHITCOMB.
